UNITED STATES PATENT OFFICE

2,272,696

ELECTRIC CIRCUITS

Patrick Foy, Chicago, Ill.

Application November 25, 1938, Serial No. 242,199

3 Claims. (Cl. 201—63)

My invention relates to an improved circuit for electric power consuming units, designed to protect the consuming units from injury to overloads or to an accidental overvoltage on the line.

With these objects in view the invention consists in the provision of a resistance unit preferably located adjacent the source of supply and adapted to protect the circuit or load as subsequently used. The invention contemplates dispensing with the necessity of fuses and similar safety devices in view of the fact that the resistance unit employed may absorb the excess load if there should be a short circuit, or cushion the surge to the consuming units upon a sudden closing or completion of the circuit. The usual practice has been to interpose a fusible member in the line which melts and thus causes the disconnection. Should such a fuse member or fusible element be not of the proper capacity, impairment or possible destruction of electrical units such as a group of lights, motor, or any electrical appliance, might ensue; but under the present invention, the initial protective or resistance member will absorb the entire or excess load as above stated, if necessary, and the resistance of this element is always sufficient to consume or absorb the surge of the consuming elements in the circuit.

An important factor in carrying out the present invention is the complete insulation of the socket for receiving a lamp or other outlet device, and the employment of circuit closing means between the socket shell and a surrounding member connected to one of the supply wires.

A further object of the invention is the provision of an improved form of circuit arrangement which may be advantageously employed in a signal system such as directional indicators on automobiles, whereby a light or signal in the form of an indicator will disclose whether or not a main signal light is in operation and functioning properly.

Other objects and advantages will appear hereinafter.

The invention consists in the electrical circuit arrangement and combinations of parts and elements hereinafter described and claimed.

The invention will be best understood by reference to the accompanying drawings forming a part of this specification, and in which:

Fig. 1 is an elevational view, mostly in section, of an initial distributing member or resistance unit;

Fig. 2 is a bottom view, partly broken away, of the member shown in Fig. 1;

Fig. 3 is a plan view, partially in section, of a distributing member or resistance unit adapted to be applied to the original member shown in Fig. 1, showing the wiring system employed;

Fig. 4 is an elevational view, partly in section on the line 4—4 of Fig. 3, of one of the lights or energy receiving members from the distribution assembly shown in Fig. 3;

Fig. 5 is a vertical sectional view taken substantially on the line 5—5 of Fig. 3;

Fig. 6 is a sectional view of the contact connections taken on the line 6—6 of Fig. 3;

Fig. 7 is a plan view of a form of circular distributing or resistance unit similar to the form shown in Figs. 1 and 2, except that the switch elements are arranged exteriorly of the element;

Fig. 8 is a vertical sectional view of the distributing member shown in Fig. 7.

Fig. 9 is a vertical sectional view of a modified form of distributing member or resistance unit employing exterior switches;

Fig. 10 is a plan view of a vehicle signal circuit employing rear left and right turn signal lights and forward circuit completing lights preferably mounted upon the cowl board of an automobile and adapted to serve as indicating signal lamps showing whether the circuit is completed to either or both of the rear signal lights;

Fig. 11 is a vertical sectional view of the right turn lights taken substantially on the line 11—11 of Fig. 10; and

Fig. 12 is a front view of the construction shown in Fig. 10.

Referring to the drawings, the initial distributing member or resistance unit is shown as including an insulated base member 15 which has mounted therein a conducting cup or outer shell 16 having an inturned flange 17, preferably mounted on the base member, and in the bottom of the cup 16 is an insulating disc 18. On this insulating disk there is provided an inner spaced lamp receiving socket 19 having an in-turned flange 20. This arrangement is particularly shown in Figs. 1 and 2 and it will be noted that the purpose is to insulate both the lamp receiving socket and the spaced cup or outer socket. The base member is provided with a center contact or terminal binding post 21 in the lamp receiving socket and feed wires 22 lead to this center contact and conducting cup 16. Feed wire 24 leads to center contact 21 and wire 25 is connected to the conducting cup 16 through binding contact 26. Feed wires 22 lead from the usual distributing block or multiple socket 23 which may receive electrical supply from plug

23a. This portion, 22, 23, 23a is merely conventional, as all that is necessary is that the hot wire from the source of supply be connected to the center contact 21 and the cold or return wire to the outer cup 16. Mounted upon the inner lamp receiving socket 19 is a contact member 27 and the circuit is completed by manipulation of a rotatable switch member 28 having a switch knob 29. A cam portion 30 is adapted to contact member 27 upon rotation of the switch element. Lamp 31, having the usual filament 32 is provided with center contact 33 and shell contact 34 on the lamp base.

Fig. 5 illustrates a distributing member, resistance unit or element having a threaded plug 35 and outward turned flange 36, all mounted upon an insulated distributing member 37 which may be of cross-shape which preferably has an insulated cover 37a. A conductor 38 connects flange 36 to a center binding post 39 and an insulated cover 40 is provided for the conductor strip or bar 38, the central contact 41 is connected to a conductor extension 42, thus creating a central distributing point 43. A multiple conducting strip 44 of T-shape or otherwise may be connected to any number of sockets or outlets. Socket shell 45 has a central contact 46 and is adapted to receive the usual lamp 47 having filament 48 and central contact 49. Lamp 47 has the usual shell contact portion 50. A single conducting strip 51 is provided to complete the circuit and for purposes of illustration there is illustrated a single socket in one switch position and a double socket contact in a second switch position. It will be understood that this may be varied as desired or as might be required. The single socket has the usual shell 52 and the central contact 53, lamp 54, filament 55, central contact 56 and shell contact 57.

A conductor 58 leads from the first shell of the multiple socket to the second shell of the multiple socket and conductor 59 leads from the second shell of the multiple socket to binding post 60. Conductor wire 61 leads from the shell of the single lamp socket to binding post 62. An operating switch 63 is adapted to close the circuit for either the single lamp or single outlet in one direction of movement, and to close the circuit to the multiple outlets in the opposite direction of movement. Operating switch 63 is pivotally mounted at 64 and arm 65 is adapted to close the circuit for the single light engagement with contact 66 through wire 67 to post 62. A conducting wire 68 leads from the central binding post 39 to pivot connection 64. Double arm 69 is utilized for completion of the multiple lamp circuit through multiple lamp switch contact 70 and wire 71 leading from binding post 60 to contact 70. A stop pin 72 may be provided to limit the throw of the switch in either direction and the switch is manipulated by a wing 73.

Referring to Figs. 7 and 8 there is provided a contact plug 74 on the collar or outer shell 16a. This contact plug is connected, for illustrative purposes, to a first take-off wire 75 for lights. A second take-off wire 76 is connected to contact member 27a on the lamp receiving socket shell shown in Fig. 8. A light 77 is representative of lighting or similar units which may be included in this circuit which is opened and closed by means of switch 78. A take-off wire 79 may be employed for a motor, for example, or other current uses, and a second take-off wire 80 completes the circuit to motor 81, controllable by switch 82.

Referring to Fig. 9, a plunger switch 83 may be

conveniently employed, and this type of switch is considered better adapted for the present form of electrical connections and mountings. Switch 83 carries a stem 84 having transverse pins 85 adapted to engage or disengage a recessed plate 86. This type of switch employs a compression spring 88 held by a spring retaining collar 87 and is operated by knob 89. The circuit is closed through the contact at the inner end of stem 84 with the binding contact or post 26. The other elements similar to like elements in Figs. 7 and 8 are correspondingly numbered. The current enters from the line 22 through 24 to 21, thence through filament 32, contact 34, shell 29, then through 27, 76 and 78 to the consuming unit 77, then through line 75 to binding post 26 which is insulated from the shell 19. With the parts in the position illustrated no current flows, but by turning the switch button 89 the pins 85 enter the depressions in 86 permitting the spring to force the stem 85, which is in electrical contact with the shell 16, into engagement with 26, thereby completing the circuit through 87, 84 to shell 16 and thence through conductor 25, which is electrically connected to shell 16, to the line 22.

Figs. 10, 11 and 12 illustrate an automobile signal system for indicating left and right turns wherein there is included in the circuit indicating lights preferably mounted upon the cowl, both for the purpose of indicating which of the directional rear signal lights is operated and also for showing whether the circuit is complete. For illustrative purposes, an insulated base 90 has mounted thereon a branch conductor element 91 and there is also provided a cover insulation 92. A branch conductor 93 leads to the central contacts 94 of the rear left and right turn lights 31. The indicating lights are carried in sockets 95 each having an outer shell 96 and an inner contact element 97. An inner contact 98 is provided for either the left or right turn indicating lights and a connection 99 is provided on the front left or right turn indicating lights. A conducting wire 100 leads from each of the sockets 95 to a corresponding contact 99. There is provided an outer shell 101 on the front indicating lights and also an inner shell 102. A conductor 103 leads to the front left turn indicating light and wire 104 to the right front indicating light.

The switch is provided with a left turn contact 105 and a right turn contact 106, both of these contacts being insulated from the metallic frame 107. A switch arm 108 is provided for selectively closing the circuit to either the left or right turn indicating lights. Pivoted crank pin 109 is provided for the switch, grounded to the frame 107, and there is also provided an operating knob 110 mounted on pin 109. The switch has a left turn leaf 111 and a right turn leaf 112, adapted to be alternately and selectively actuated by the switch member. For illustrative purposes, the usual storage battery 113 is shown.

Thus in the operation of the various devices and circuits in the forms and exemplifications shown and described, the distributing unit includes an electric circuit which comprises an initial resistance unit or distributing member connected to an output circuit with ultimate consuming units or appliances of any desired character, the initial resistance unit being connected in series with the output circuits so that when operated by connection or through the medium of a switch, as previously described, said current consuming units will be protected from harm by

the resistance unit or distributing member and the objections heretofore outlined overcome.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent, is:

1. A protective unit for an electric circuit comprising a base, a pair of substantially concentric shells of conductive material mounted on said base and insulated from the same and from each other, one of said shells forming a socket for a resistance unit, a resistance therein, an insulated central contact member for said resistance unit, means for connecting said contact member to the supply wire of a supply line, means on the resistance supporting shell for connecting a conductor to a consuming unit, means on the other shell for connecting the return conductor from said consuming unit, means for connecting the last mentioned shell to the return wire of the supply line and a switch interposed in the return wire.

2. A protective unit for an electric circuit, comprising a base, a pair of substantially concentric shells of conductive material mounted on said

- base and insulated from the same and from each other, one of said shells forming a socket for a resistance unit, a resistance unit therein, an insulated central contact member for said resistance unit, means for connecting said contact member to the supply wire of a supply line, means on the resistance supporting shell for connecting a plurality of conductors to a plurality of consuming units, means on the other shell for connecting the return conductors from said consuming units, means for connecting the last mentioned shell to the return wire of the supply line and a switch in each of said return wires between the respective consuming unit and the outer shell.
- 5 3. A protective unit for an electric circuit comprising a base, inner and outer concentric shells of conductive material mounted on said base and insulated from the same and from each other, the inner shell forming a socket for a resistance unit, a resistance unit therein, an insulated central contact member for said resistance unit, means for connecting said contact member to one wire of a supply line, means on the inner shell 20 for connecting a conductor to a consuming unit, means on the outer shell for connecting the return conductor from said consuming unit, and means for connecting the last mentioned shell to the other wire of the supply line and a switch in 25 the outer shell for controlling the connection between the same and said other wire of the supply line.
- 30

PATRICK FOY.
